UNITED STATES PATENT OFFICE

158,960

MOTORCYCLE FRONT END UNIT

William J. Harley, Milwaukee, Wis., assignor to
Harley-Davidson Motor Co., Milwaukee, Wis., a
corporation of Wisconsin

Application May 9, 1949, Serial No. 2,531

Term of patent 14 years

(Cl. D90—8)

To all whom it may concern:

Be it known that I, William J. Harley, a citizen of the United States, residing at Milwaukee, in the county of Milwaukee and State of Wisconsin, have invented a new, original, and ornamental Design for a Motorcycle Front End Unit, of which the following is a specification, reference being had to the accompanying drawing, forming part thereof.

Fig. 1 is a perspective view of a motorcycle front end unit showing my new design;

Fig. 2 is a perspective view as seen from the opposite side thereof; and

Fig. 3 is a top plan view.

The dominant feature of my design resides in that portion shown in full lines in the drawing.

I claim:

The ornamental design for a motorcycle front end unit, as shown.

WILLIAM J. HARLEY.
